RAILWAY TRACK CIRCUIT APPARATUS

Paul N. Martin, Swissvale, Pa., assignor to The Union Switch & Signal Company, Swissvale, Pa., a corporation of Pennsylvania

Application August 30, 1933, Serial No. 687,476

22 Claims. (Cl. 246—41)

My invention relates to railway track circuit apparatus, and more specifically to apparatus for improving the shunting characteristics of railway track circuits.

5 I will describe several forms of apparatus embodying my invention, and will then point out the novel features thereof in claims.

In the accompanying drawings, Fig. 1 is a diagrammatic view showing one form of apparatus embodying my invention. Figs. 2 to 10, inclusive, are diagrammatic views showing modified forms of the apparatus illustrated in Fig. 1, also embodying my invention.

Similar reference characters refer to similar parts in each of the several views.

In the form of track circuit commonly employed for railway signaling, the shunting sensitivity varies over a wide range, due chiefly to variations in ballast leakage from rail to rail and the consequent changes in the energization 20 of the track relay. That is, when the ballast is wet and the resulting leakage high, the track relay energy level is low, and a train shunt of relatively high resistance is capable of releasing 25 the track relay. However, under dry ballast conditions, the track relay energization may become abnormally high, so that difficulty may be experienced in obtaining safe shunting under various operating conditions. The use of a current-limiting impedance at the feed end of the track 30 circuit, although helpful, does not of itself provide sufficiently close regulation of the track relay energy to be entirely satisfactory.

For uniform shunting sensitivity, it is desirable 35 to maintain the normal track relay energy level, prior to the time when the shunt is applied, as nearly uniform as possible, irrespective of ballast leakage, and it is believed that this result can be accomplished most effectively by the use 40 of regulating apparatus located at the relay end of the track circuit. Apart from the effect of ballast leakage on track relay energization, there is an additional factor which noticeably decreases 45 the maximum shunting sensitivity of a track circuit. This factor results from the practical limitation to which track relays are subject, namely, that the energization at pickup must be greater than the energization at release. Therefore, although improved shunting could be obtained by maintaining the energization of the 50 track relay at the release value, some sensitivity must be sacrificed in the usual track circuit because the energization must be at least sufficiently high for pickup of the relay. My invention makes it possible to eliminate partly or

wholly the effect of the spread between the pickup and release values, as well as to offset the disadvantages due to ballast leakage variation, thus providing increased shunting sensitivity as well as decreased shunting time.

5 Referring to Fig. 1, I have shown a section of railway track F—G, one end of which is supplied with rail current from a suitable source 2, through an adjustable limiting impedance 3. Connected across the rails at the other end of the 10 section is a track relay A, in the energizing circuit of which is included, at times, a resistor R. Relay A controls a pickup circuit for an auxiliary relay B, by means of front contact 4. When relay B is picked up, back contact 5 being open, 15 the short circuit is removed from resistor R, thereby decreasing the energization of relay A.

Let it first be assumed that relay B is used to decrease the effect of the spread between pickup and release values of relay A. Under normal 20 conditions with section F—G unoccupied, both relays A and B will be picked up. The value of resistor R will be determined by the minimum ballast condition, so that the amount of energy which is permitted to remain in relay A will depend to a large extent on the track circuit regulation. If the regulation is good, so that the rail voltage at the relay end does not vary widely 25 with ballast conditions, resistor R may be chosen of such a value as will decrease the energy level in relay A almost to the release point. Maximum shunting sensitivity can be obtained with such an adjustment, assuming other factors to remain constant.

When a train enters section F—G, relay A 35 will release, opening front contact 4 to release relay B. As soon as relay B releases, back contact 5 will become closed to shunt out resistor R. Consequently, as soon as the train leaves the section, the energization of relay A will be sufficient 40 for pickup, and the circuit will be restored to the condition illustrated. From the foregoing, it will be apparent that by a suitable choice of the value of resistor R with reference to the release point of relay A, the shunting sensitivity 45 of the ordinary track circuit can be greatly improved. As is well known, track relays particularly of the direct current type, have an appreciable spread between the pickup and the release energy levels, with the result that the train shunt 50 must be sufficiently effective to by-pass the increment of current above the release point of the relay. Not only does this require a lower resistance train shunt, but the shunting time is also substantially increased because the relay flux re- 55

quires a longer time to die down from the higher level. A further advantage arising from the use of the resistor R is that the addition of resistance in series with the inductance of relay A results in a much more rapid flux decay, i. e., lower shunting time, than can be obtained at the same value of current but without the series resistance. This result will be understood from a consideration of the time constant of an inductive circuit having resistance in series therewith. Practically, the combination of relays A and B is in many respects the equivalent of a single track relay having pickup and release values which are substantially the same.

Let it next be assumed that relay B and resistor R are used for improving track relay voltage regulation. If the impedance of relay B is made substantially higher than that of relay A, and if the limiting impedance 3 is so adjusted that with low ballast resistance relay A will just pick up, then when the ballast dries out and the track voltages rises, relay B will pick up. The pickup of relay B will remove the excess energization from relay A, under the dry ballast condition. The resistor R must be of sufficiently high value to insure that relay A will release prior to the release of relay B, otherwise the increased shunting sensitivity will be sacrificed. Because of the relatively high impedance of relay B, this relay will have only a slight effect on the operation of the track circuit under conditions of low ballast resistance. With high ballast resistance, however, when the shunting sensitivity ordinarily becomes very low, the addition of resistor R in series with relay A will greatly increase the shunting sensitivity, as well as decrease the shunting time. Relay A is provided with an additional contact, such as 20, which may be used to control circuits for signals, or any other traffic governing apparatus.

Referring to Fig. 2, which is identical with Fig. 1 except for the addition of a second auxiliary relay C in parallel with relay B, the operation of the apparatus of this figure, in view of the foregoing description, will be clear without further explanation. Relay C is of higher impedance than relay B, and acts to cut in an additional resistor R¹, by means of back contact 6, when the ballast resistance and the resulting track voltage become sufficiently high for pickup of relay C. In this manner, track circuits having a large ballast resistance variation can be operated safely. If desired, relay C can be used merely as an adjunct to relay B, to permit adding the series resistance in two small steps, rather than one large step, thus aiding to maintain the shunting sensitivity more uniform throughout the operating range of the relay combination. It will be apparent that if a sufficient number of auxiliary relays is used, the shunting sensitivity of the track circuit can be maintained at a uniformly high value, notwithstanding a variation of track voltage between wide limits.

In Fig. 3, the auxiliary relay B¹, instead of being connected across the two rails of the track as in Fig. 1, is connected in series with relay A¹. Relay B¹ is a low impedance current relay having the same functions as relay B in Fig. 1. In explaining the operation of the apparatus, I shall assume that the track circuit current has been adjusted under wet ballast conditions to that value which will enable relay A¹ to pick up. Since the pickup current of relay B¹ is considerably

B¹ will be deenergized under the above condition, and the energizing circuit for relay A¹ will include the back point of contact 8 of relay B¹, wire 21, and the winding of relay B¹. As the ballast dries out, the current through relay B¹ will increase until a point is reached at which relay B¹ will pick up.

As soon as relay B¹ picks up, resistor R will be connected in series with relay A¹ over the front point of contact 8 of relay B¹, thus compensating for the increase in track voltage. At the same time, front contact 9 of relay B¹ will close, connecting resistor R² which replaces the winding of relay A¹, into the circuit of relay B¹, in order that relay B¹ may remain energized even though the current through relay A¹ is substantially decreased. Contact 8 of relay B¹ is of the continuity transfer type in order that the energizing circuit of relay A¹ will not be interrupted during the pickup of relay B¹.

When a train enters the track section, relay A¹ will release first, followed by the release of relay B¹ which, in closing the back point of contact 8, prepares the low resistance circuit for pickup of relay A¹ as soon as the train leaves the section. The operating characteristics of relays A¹ and B¹ should be such that relay A¹ will be the first to pick up when a train leaves the section, and the first to release when a train enters the section. Should relay B¹ pick up ahead of relay A¹, resistor R might prevent the pick-up of relay A¹, or at least retard the pickup unnecessarily. If relay B¹ were permitted to release ahead of A¹ upon shunting of the track, the shunting sensitivity would be decreased because of the higher energization of relay A¹ under this condition. By energizing relay B¹ over the front contact 7 of relay A¹, a relatively quick release of relay B¹ and one which is necessarily subsequent to the release of relay A¹ is obtained.

Referring to Fig. 4, the circuit of this figure shows a method for obtaining compensation for the spread between the pickup and release current values, independently of the compensation for high track voltage under dry ballast conditions. Separate resistors R³ and R⁴, respectively, are provided for this purpose. The signal control relay D is a repeater of the track relay A², and is of the slow pickup and slow release type. By employing relay D for signal control purposes, it becomes possible to use a highly sensitive track relay A², since the mechanical work required of relay A² is very small.

In explaining the operation of the apparatus of Fig. 4, I shall assume that under the condition of minimum ballast resistance, the track energy has been adjusted to a value which is sufficient to pick up relay A², it being understood that the track voltage required to pick up the auxiliary relay B² is substantially higher than that required to pick up the track relay A². When relay A² picks up, front contact 11 will close and the repeater relay D will become energized from a suitable current source having the terminals X—Y. As soon as relay D picks up, back contact 12 will open, thereby opening the branch circuit around resistor R³, so that resistor R³ will be included in the energizing circuit of relay A², to compensate for the spread between pickup and release current values. A time interval is introduced into the pickup of relay D in order that relay A² will reach its fully energized condition before the energization is decreased through the opening of back contact 12. Should contact 12 be permitted to open before the armature of relay A² will have reached its fully closed condition, an undesired release of relay A²

might occur, with resulting "pumping" action between the two relays A² and D. This difficulty would be particularly prominent under wet ballast conditions, when the track relay energization is low. Another reason for retarding the pickup of relay D is to prevent a momentary clear signal from being displayed, should relay A² pick up momentarily due to a temporary loss of shunt. The slow release characteristic of relay D merely introduces an additional time delay before a change of signal indication may occur, thus providing more time within which a low resistance shunt can be established when the shunting is intermittently poor.

When the ballast becomes dry and the track voltage rises, relay B² will pick up, opening the branch circuit around resistor R⁴ to add this resistor also, in series with relay A². When a train enters the track section, relay A² will release first, followed by relays B² and D. Thereupon, both resistors R³ and R⁴ will be short-circuited, in preparation for the pickup of relay A² as soon as the train leaves the section.

Referring to Fig. 5, the apparatus of this figure operates in the same manner as the apparatus of Fig. 4. The normal energizing circuit of relay A³ does not include a front contact of relay A³ as this contact can be eliminated if relay D¹ is of the non-slow release type. Relay D¹ should preferably have a slow pickup characteristic, for the same reasons advanced in connection with relay D of Fig. 4.

In the modified form of apparatus shown in Fig. 6, the shunting sensitivity of relay A⁴ is increased and the shunting time decreased not only by adding resistance in series with the relay winding, but also by decreasing the effective turns of the winding. The operation is as follows: When the ballast is wet, relay A⁴ will be energized and relay B⁴ deenergized, so that the circuit of relay A⁴ will include both windings 13 and 14 of the relay, and the back point of the continuity transfer contact 15. If the track voltage increases sufficiently to pick up relay B⁴, the circuit of relay A⁴ will include only portion 13 of the relay winding, resistor R⁵, and the front point of contact 15 of relay B⁴. By properly proportioning the number of turns which are cut out and the value of resistor R⁵, with respect to the track voltage at which relay B⁴ picks up, the release characteristic of relay A⁴ may be raised sufficiently, under the dry ballast condition, to make the shunting sensitivity fully as satisfactory as under the wet ballast condition. The shunting time will, in addition, be much lower with dry ballast because the flux decay will be accelerated due to decreased inductance as well as increased resistance of the circuit. If it is desired to eliminate the bridging feature of contact 15, this may be done by placing a permanent connection around the front point of contact 15, without affecting the operation of the circuit in a substantial manner.

Referring to Fig. 7, the circuit of this figure represents a modification of the circuit of Fig. 4, the chief difference being that the auxiliary relay B⁵ is controlled by the track repeater relay D², instead of being controlled by the track relay directly. When the track relay controls the auxiliary relay directly, as soon as the track relay picks up and before it has attained its fully energized condition, the auxiliary relay becomes connected across the track, and if the ballast is wet, the added load may be sufficient to cause the track relay to release, unless a com-

pensating adjustment of the current-limiting impedance at the feed end of the track circuit is made. Some sacrifice of shunting sensitivity results from such an adjustment. By controlling relay B⁵ over the front point of contact 16 of relay D², relay D² being preferably of the slow-pickup type, relay A⁵ has ample time within which to reach its fully closed condition, before the current of relay B⁵ is added to the track circuit load, so that ordinarily, the adjustment as of the track impedance can remain the same as though relay B⁵ were not used.

The arrangement shown in Fig. 8 is similar to Fig. 1, except that a time delay relay T of any suitable type, is added to insure that once the track relay A⁶ has released, it will remain de-energized until such time, at least, as is required for relay T to complete its pickup movement. In this manner undesired changes of signal indication arising from momentary loss of shunt are prevented. When relay A⁶ releases, relay T becomes energized over back contact 17, and closes its front contact 18, to close the energizing path for relay A⁶, around the open front contact 19.

The apparatus of Fig. 9 is similar to that of Fig. 3, differing chiefly in that the relay B¹ of Fig. 9 is controlled over a back contact of the track relay A¹ rather than a front contact of this relay. Relay B¹ is designed to have a higher pickup value than relay A¹. In operation, the track circuit is so adjusted that relay A¹ will just pick up under the most unfavorable ballast condition. When the ballast resistance increases sufficiently, relay B¹ will pick up over a circuit which includes the winding of relay A¹ and the back point of contact 22. The opening of the back point of contact 22 will cause resistor R to be inserted in series with relay A¹, and the closing of the front point of this contact will connect resistor R⁶ in parallel with relay A¹, thus reducing the energization to increase the shunting sensitivity.

Relay A¹ is designed to release ahead of relay B¹, so that when the track is shunted, relay A¹ will release, and in closing back contact 21 will short-circuit relay B¹, causing it to release also. With relay B¹ released, the pickup circuit for relay A¹ is restored, so that the track relay will pick up as soon as the train leaves the section.

Referring to Fig. 10, the apparatus of this figure is similar to that of Fig. 9, differing chiefly in that the relay A⁴ has a tapped coil, for reasons brought out more fully in the description of Fig. 6. The pickup circuit for relay A⁴ includes both of the relay windings 13 and 14, back point of contact 15, and the winding of relay B⁴. The track circuit is so adjusted that relay A⁴ will just pick up under the most unfavorable ballast condition. Relay B⁴, having a substantially higher pickup value, will remain released under this condition. When the ballast dries out, relay B⁴ will pick up, opening the circuit for winding 14 at the back point of contact 15, and inserting resistor R⁵ in series with winding 13 by virtue of the closing of the front point of contact 15.

In order to prevent relay A⁴ from releasing during the pickup interval of relay B⁴, contact 15 is made of the continuity transfer type. If it is desired to eliminate the bridging feature of contact 15, this may be done by placing a permanent connection around the front point of contact 15 so that the holding circuit for relay A⁴ will always be closed, irrespective of whether

the pickup circuit is or is not closed at the back point of contact 15. The operation under this condition will be the same as described above.

When a train enters the section, relay A⁴ will release ahead of relay B⁴, closing back contact 23 which short circuits relay B⁴. As soon as relay B⁴ releases, relay A⁴ will have its pickup circuit restored through the closing of the back point of contact 15, in readiness for the pickup

10 operation as soon as the train leaves the section.

Although direct current track circuits and direct current relays have been illustrated for simplicity, it will be apparent that the fundamental principles of connecting one or more impedances after pickup of the track relay, or altering the number of turns, or both, as a means for increasing the shunting sensitivity and decreasing the shunting time, can be applied as well to track circuits of the alternating current type, or those employing any other suitable form of electrical energy.

25 Although I have herein shown and described only a few forms of apparatus embodying my invention, it is understood that various changes and modifications may be made therein within the scope of the appended claims without departing from the spirit and scope of my invention.

Having thus described my invention, what I

30 claim is:

1. In combination with a section of railway track and a source of current connected across the rails of said section, a track relay and an auxiliary relay, a pickup circuit for said track relay connected across the rails of said section and including a back contact of said auxiliary relay, a circuit for said auxiliary relay connected across the rails of said section and including a front contact of said track relay, and an impedance connected across said back contact for decreasing the energization of said track relay to improve the shunting sensitivity of said track section.

2. The method of increasing the shunting sensitivity of a railway track circuit, which comprises connecting a track relay and an auxiliary relay in such manner that both receive energy over the rails of the track circuit, said auxiliary relay having a pick-up value of track voltage 50 higher than that required for pickup of said track relay, and using said auxiliary relay when picked up to decrease the energization of the track relay by means of a normally ineffective impedance which becomes effective when and only when said auxiliary relay is picked up thereby rendering said track circuit more sensitive to shunting.

3. The method of increasing the shunting sensitivity of a railway track circuit and decreasing the shunting time, which comprises connecting a track relay and an auxiliary relay in such manner that both receive energy over the rails of the track circuit, said auxiliary relay having a pick-up value of track voltage higher than that required for pickup of said track relay, and using said auxiliary relay when picked up to add a resistor in series with said track relay to decrease the energization thereof and to accelerate the flux decay in the core thereof, said resistor being normally ineffective and becoming effective when and only when said auxiliary relay is picked up.

4. In combination with a section of railway

75 track and a source of current connected across

the rails of said section, a track relay and an auxiliary relay, a pickup circuit for said track relay connected across the rails of said section and including a back contact of said auxiliary relay, a branch path around said track contact including a resistor, and a circuit for said auxiliary relay connected across the rails of said section and including a front contact of said track relay.

5. In combination with a section of railway 10 track and a source of current connected across the rails of said section, a track relay and an auxiliary relay, a pickup circuit for said track relay connected across the rails of said section and including the winding and a back contact 15 of said auxiliary relay, a holding circuit for said track relay connected across the rails of said section and including a front contact of said auxiliary relay, and a circuit for said auxiliary relay including a second front contact thereof 20 and a front contact of said track relay.

6. In combination with a section of railway track and a source of current connected across the rails of said section, a track relay and an auxiliary relay, a pickup circuit for said track 25 relay connected across the rails of said section and including the winding and a back contact of said auxiliary relay, a holding circuit for said track relay connected across the rails of said section and including a front contact of said auxiliary relay and an impedance for decreasing the energization of said track relay; and a circuit for said auxiliary relay including a second front contact thereof, a front contact of said track relay, and a second impedance of substantially the same magnitude as the impedance of 35 said track relay.

7. In combination with a section of railway track and a source of current connected across the rails of said section; a track relay, an auxiliary relay, and a slow pickup track repeater relay; 40 a pickup circuit for said track relay connected across the rails of said section and including a back contact of said repeater relay as well as a back contact of said auxiliary relay, a first branch path around said back contact of the repeater relay 45 including a front contact of the track relay and an impedance, a second branch path around said back contact of the auxiliary relay including a second impedance, a holding circuit for said track relay connected across the rails of said section 50 and including said first branch path, a circuit for said repeater relay including a second front contact of said track relay, and a circuit for said auxiliary relay including a third front contact of 55 said track relay.

8. In combination with a section of railway track and a source of current connected across the rails of said section; a track relay, an auxiliary relay, and a slow pickup track repeater relay; 60 a pickup circuit for said track relay connected across the rails of said section and including a back contact of said repeater relay as well as a back contact of said auxiliary relay, a first branch path around said back contact of the repeater relay including a front contact of the 65 track relay and an impedance, a second branch path around said back contact of the auxiliary relay including a second impedance, a holding circuit for said track relay connected across the rails of said section and including said first branch path, 70 a locally energized circuit for said repeater relay including a second front contact of said track relay, and a circuit for said auxiliary relay connected across the rails of said section and including a third front contact of said track relay.

9. In combination with a section of railway track and a source of current connected across the rails of said section; a track relay, an auxiliary relay, and a slow pickup track repeater relay; 5 a pickup circuit for said track relay connected across the rails of said section and including a back contact of said repeater relay as well as a back contact of said auxiliary relay, a first branch path around said back contact of the repeater relay including an impedance, a second branch path around said back contact of the auxiliary relay including a second impedance, a holding circuit for said track relay connected across the rails of said section and including said first branch 10 path, a circuit for said repeater relay including a front contact of said track relay, and a circuit for said auxiliary relay including a second front contact of said track relay. 15
10. In combination with a section of railway track and a source of current connected across the rails of said section; a track relay, an auxiliary relay, and a slow pickup track repeater relay; a pickup circuit for said track relay connected across the rails of said section and including a back contact of said repeater relay as well as a back contact of said auxiliary relay, a first branch path around said back contact of the repeater relay including a resistor, a second branch path around said back contact of the auxiliary relay 20 including a second resistor, a holding circuit for said track relay connected across the rails of said section and including said first branch path, a locally energized circuit for said repeater relay including a front contact of said track relay, and a circuit for said auxiliary relay connected across the rails of said section and including a second front contact of said track relay. 25
11. In combination with a section of railway track and a source of current connected across the rails of said section; a track relay, an auxiliary relay, and a track repeater relay; a pickup circuit for said track relay connected across the rails of said section and including a back contact of said repeater relay, a holding circuit for said track relay connected across the rails of said section and including a front contact of the track relay as well as a back contact of the auxiliary relay, a branch path around said back contact of the auxiliary relay including an impedance, a circuit for said repeater relay including a second front contact of said track relay, and a circuit for said auxiliary relay including a front contact of said repeater relay. 30
12. In combination with a section of railway track and a source of current connected across the rails of said section; a track relay, an auxiliary relay, and a track repeater relay; a pickup circuit for said track relay connected across the rails of said section and including a back contact of said repeater relay; a holding circuit for said track relay connected across the rails of said section and including a front contact of the track relay, an impedance, and a back contact of said auxiliary relay; a branch path around said back contact of the auxiliary relay including a second impedance, a circuit for said repeater relay including a second front contact of said track relay, and a circuit for said auxiliary relay including a front contact of said repeater relay. 35
13. In combination with a section of railway track and a source of current connected across the rails of said section; a track relay, an auxiliary relay, and a track repeater relay; a pickup circuit for said track relay connected across the rails of said section and including a back contact 40
14. In combination with a section of railway track and a source of current connected across the rails of said section, a track relay, a pickup circuit for said track relay connected across the rails of said section, an auxiliary relay which requires a higher track voltage for pickup than said track relay, a pickup circuit for said auxiliary relay including the rails of said section and effective only when said track relay is picked up, and normally ineffective means governed by a contact of said auxiliary relay and effective when the auxiliary relay is picked up for decreasing the energization of said track relay to increase the 45 shunting sensitivity of said track section. 50
15. In combination with a section of railway track and a source of current connected across the rails of said section; a track relay and an auxiliary relay both energized from said source over the rails of said section, the energization of said auxiliary relay occurring only if said track relay is picked up, said auxiliary relay having a pickup track voltage characteristic higher than the pickup track voltage characteristic of said track relay; and normally ineffective means governed by said auxiliary relay and effective when and only when the auxiliary relay is picked up for raising the release characteristic of said track relay to increase the shunting sensitivity of said 55 track section. 60
16. In combination with a section of railway track and a source of current connected across the rails of said section; a track relay and an auxiliary relay both energized from said source over the rails of said section, the energization of said auxiliary relay occurring only if said track relay is picked up, said auxiliary relay having a pickup track voltage characteristic higher than the pickup track voltage characteristic of said track relay; and normally ineffective means governed by said auxiliary relay and effective when and only when the auxiliary relay is picked up for decreasing the time constant of said track relay to accelerate the flux decay therein, thereby 65 decreasing the time required to shunt said track relay. 70
17. In combination with a section of railway track and a source of current connected across the rails of said section, a track relay and an auxiliary relay, a pickup circuit for said track relay connected across the rails of said section and including the winding and a back contact of said auxiliary relay, means controlled by said track relay for releasing said auxiliary relay when the track relay is released, and means controlled by said auxiliary relay effective when the auxiliary relay is energized for decreasing the energization of the track relay to improve the shunting sensitivity of said track section. 75
18. In combination with a section of railway track and a source of current connected across the rails of said section, a track relay and an auxiliary relay having a given pickup value which is higher than the pickup value of said track 75

- relay, a pickup circuit for said track relay connected across the rails of said section and including the winding and a back contact of said auxiliary relay, said pickup circuit serving also to pick up said auxiliary relay when the track voltage is at or above said given value, means controlled by said auxiliary relay effective when the auxiliary relay is picked up for decreasing the energization and increasing the rate of flux decay in the core of said track relay, and means controlled by said track relay effective when said track relay is released for releasing said auxiliary relay.
19. In combination with a section of railway track and a source of current connected across the rails of said section, a track relay and an auxiliary relay both receiving current from said source over the rails of said track, and normally ineffective means controlled by a contact of said auxiliary relay and effective upon the pick-up of the auxiliary relay for decreasing the energization of said track relay to improve the track shunting sensitivity.
20. In combination with a section of railway track and a source of current connected across the rails of said section, a track relay and an auxiliary relay both receiving current from said source over the rails of said track, a normally

ineffective resistor, and means controlled by a contact of said auxiliary relay and effective upon the pick-up of the auxiliary relay for adding said resistor in series with said track relay to decrease the energization thereof and to accelerate the flux decay in the core thereof.

21. In combination with a section of railway track and a source of current connected across the rails of said section, a track relay and an auxiliary relay both receiving current from said source over the rails of said track, and normally ineffective means effective only upon the pickup of said auxiliary relay for increasing the track voltage value at which said track relay will release. 15

22. In combination with a section of railway track and a source of current connected across the rails of said section, a track relay and an auxiliary relay both receiving current from said source over the rails of said track, a normally ineffective impedance, and means effective only upon the pickup of said auxiliary relay for connecting said impedance in series with said track relay to thereby decrease the track relay energization and improve the track shunting sensitivity. 20
